NON-BULGING FRUIT BOX

Walter C. George, St. Louis, Mo., assignor, by mesne assignments, to Crown Zellerbach Corporation, San Francisco, Calif., a corporation of Nevada

Application October 19, 1955, Serial No. 541,400

2 Claims. (Cl. 229—14)

The invention relates to containers which are substantially proof against side wall outward deflection or bulging, especially when loaded with fresh fruit and hydro-cooled prior to shipment.

Fresh fruit or the like is usually pre-cooled just prior to loading, for example, in railroad cars, by passing packed containers of the fruit through a hydro-cooler. A common cause of failure of containers for this purpose is the weakening of the walls by undue absorption of moisture, resulting in highly objectionable outward deflection or bulging thereof.

The container of a preferred form of the invention is rectangular in shape, comprising inner and outer full telescoping sections with an inner liner. The outer and inner telescoping sections are each closed by flaps attached to the top and bottom edges respectively of the side and end walls. The liner comprises a solid bottom panel of somewhat lesser length and breadth than the bottom panel of the inner body section. Flaps integral with each side and end edge of the liner bottom panel are disconnected from each other and extend upwardly, flaring slightly outwardly, and the upper margins thereof are reversely folded over the top edges of the body section walls at a height which automatically positions the bottom panel of the liner about $\frac{1}{2}$ to $\frac{3}{4}$ " above the bottom panel of the body section.

When the liner is positioned within the inner section as described, it functions, in effect, as a cradle suspended from the upper free edges of the inner section walls in spaced relation from the section walls and bottom panel thereof. When the liner is filled with fruit, the weight thereof, supported solely by the upper free edges of the container, depresses the suspended bottom panel of the liner slightly which deflection simultaneously draws the side panels slightly inwardly so that the liner absorbs substantially all of the outward thrust of the contents. The tendency of the side walls of the container to bulge outwardly, especially when the loaded container is pre-cooled, is effectively eliminated.

When the fruit is to be hydro-cooled before shipment, and the telescoping cover section is constructed of relatively heavy paperboard such as double face corrugated board to provide top load requirements, the invention permits the use of relatively light solid fibreboard in the body section and liner with resulting overall economy of material.

An object of the invention is to provide a container for shipping fresh fruit which may be loaded and passed through a hydro-cooler prior to shipment with substantially no resulting outward deflection or bulging of the side walls thereof.

Another object is to provide a container for packaging, pre-cooling and shipping fresh fruit and the like, comprising an inner body section with a cradle-like liner suspended from the top edges of the walls for containing the contents free from contact with the body bottom panel and walls, enclosed in an outer full telescoping cover section.

2

Still another object is to provide a shipping container of high stacking strength for fresh fruit comprising an inner section constructed of solid fibreboard with a liner, also of solid fibreboard, suspended from the upper edges 5 of the body walls enclosed in a full telescoping outer section constructed of corrugated paperboard, the walls of the liner being of slightly less height than the walls of the inner section and the bottom panel of the liner being of slightly less length and width than the bottom closure 10 of the body section, whereby all portions of the liner are spaced inwardly from like parts of the body section.

Other objects and advantages of the invention will be readily apparent in the following description and the accompanying drawing in which:

15 Fig. 1 is a plan view of the blank which forms the inner body section;

Fig. 2 is a perspective view of the assembled inner body section;

Fig. 3 is a plan view of the blank from which the inner liner is assembled;

Fig. 4 is an exploded perspective view of the body section with the fully assembled liner positioned thereabove;

Fig. 5 is an end view of the completely assembled inner body section;

25 Fig. 6 is a sectional view of the body section shown in Fig. 5 taken in the direction of the arrows 6—6;

Fig. 7 is a vertical section through the container shown in Fig. 5 taken along the direction of the arrows 7—7;

Fig. 8 is a vertical section taken along the median line 30 of the fully assembled loaded container.

The blank for forming a preferred form of the body section of the container is indicated at A, Fig. 1. The blank is scored longitudinally at 10 and transversely at

35 11, defining end walls 12, side walls 13 and connecting flap 14. The upper edge of the end and side walls are notched at substantially their midwidth at 15 for a purpose to be hereinafter described. End wall bottom closure flap 16 and side wall bottom closure flaps 17 are hinged to the respective walls along the horizontal score 10 and are

40 separated from each other by slots 18 extending from the outer edges thereof to the horizontal score 10. The notches 18 are preferably alternately offset from the planes of transverse scores 11 to facilitate folding of the closure flaps in the course of assembly of the blank.

45 The blank A is shown fully assembled in Fig. 2 with the connecting flap 14 secured to the remote end wall 12 by staples 19 or other suitable means and bottom closure flaps folded right angularly inward in closed position.

The blank for forming the inner liner of the body section is shown at B, Fig. 3. Longitudinal scores 20 and transverse scores 21 define the bottom panel 22 of the liner and the hinge lines of the liner side walls 23 and end walls 24 respectively. The scores 20 and 21 are positioned to

55 provide the bottom panel 22 of slightly less length and width than the bottom closure of the body section. The outer margin of each of the liner walls is double scored at 25 to define flanges 26 which are reversely folded into parallel spaced relation to the outer face of the liner walls and secured in the described position preferably by a

60 single staple 27 applied approximately midway the length of the flanges 26. The spaces between the upper margins of the liner walls and the inner faces of the flanges 26 provide channels adapted to receive the upper edges of the body walls. The double scores 25 are spaced from the longitudinal scores 20 and transverse scores 21 a distance

65 somewhat less than the height of the walls 12 and 13 of the body section, thereby suspending the bottom panel of the liner about $\frac{1}{2}$ to $\frac{3}{4}$ of an inch above body section bottom panel with the liner walls spaced inwardly from

70 the section walls when the liner is inserted therein.

A convenient method of assembling the container is to fold the end walls 12 and side walls 13 about the

transverse scores 11 to form a rectangular tube and attaching the connecting flap 14 to the free side edge of the remote end panel 12 by staples 19, glue or other suitable means. The end wall bottom closure flaps 16 are folded right angularly inwardly and the side wall bottom closure flaps 17 also folded right angularly inwardly over the folded end wall flaps and the flaps secured together by glue, staples or other suitable means. The fully assembled body blank is shown in perspective in Fig. 2.

The blank B, forming the liner of the body section, may be readily assembled by folding the flanges 26 outwardly and downwardly in parallel relation to the outer face of the liner walls 23 and 24 and securing them preferably by staples 27. The side walls 23 and end walls 24 are then folded upwardly into position to insert into the body section and will be at an angle slightly greater than 90° with relation to the bottom panel 22 of the liner. The exploded perspective drawing, Fig. 4 shows the pre-assembled liner preparatory to insertion into its final position within the body section. When the liner is lowered into the body section, the reversely folded flanges 26 automatically telescope the upper outer margin of the side and end walls, the upper free edges of the container walls 12 and 13 seating in the base of the folds of the flanges about the double score 25. The portions of the flanges 26, which are tightly secured against the liner walls by the staples 27, seat in the cutouts 15 in the top edges of the body walls, thus permitting the unsecured portions of the folded flanges, which in effect form pockets, to ride over the top margins of the container of the body walls.

The completely assembled body section with the liner in assembled position therein is shown in Fig. 5 while Fig. 6 illustrates the detail of the flanges 26 and staples 27 through a vertical section of the body section shown in Fig. 5 in the direction of the arrows 6—6. Fig. 7 illustrates the spacing of the bottom panel 22 of the liner above the bottom closure of the body section and the slightly inwardly and downwardly converging inner walls. The clearance between the inner and outer bottom panels may be varied somewhat depending upon the size of the container, the object being to provide a space for the downward deflection of the liner bottom panel under load as shown in the sectional view of Fig. 8. By this arrangement of parts the weight of the contents of the container is uniformly distributed on the upper edges of the side and end walls of the body section, the inwardly inclined walls of the liner absorbing any outward thrust by the contents, leaving the walls of the body section free of any tendency to outward deflection or bulging.

Upon completion of the loading and pre-cooling of the container and contents, a full telescoping cover section indicated at 28 in Fig. 8, preferably constructed of double face corrugated board, is telescoped over the body section and inner liner loaded with fruit and the container is ready for shipment. Elimination of the outward deflection of the side walls of the body section when the con-

tainer is loaded facilitates the telescoping of the cover section which otherwise might be quite difficult, if not impossible, to properly position over the body section of pre-cooled loaded containers.

It is to be understood that the embodiment herein described is illustrative and not restrictive, and it is also to be understood that the invention may be susceptible of embodiment in other modified forms, and that all such modifications which are similar or equivalent hereto come equally within the scope of the claims next appearing.

What I claim is:

1. In a container for packaging and shipping a commodity, the container comprising a body section and a unitary liner section nested within the body section, the liner section including a closed bottom and upstanding opposed side walls foldably connected thereto, upper marginal end portions of at least a pair of opposed liner side walls being outwardly and downwardly turned on a fold line into substantial parallelism with the adjacent portion of the side wall and each forming a supporting flange for the liner section, separate fastening means between the ends of each downturned flange and securing a portion of each downturned flange in face engagement with the respective liner side wall, the unsecured portion of each flange being spaced from its side wall and forming pockets therewith, the body section comprising connected together upstanding wall panels integral with a substantially flat bottom, at least a pair of opposed body wall panels having cut-outs in their upper marginal portions forming notches and adjacent edge portions, said adjacent edge portions being received in said pockets, and said face contacting portion of the flange and part of the securing means being received in said notches wherein said liner section is supported on said body section by said flanges and in locked condition with said body walls.
2. The container as defined in and by claim 1 wherein the height of the side walls of the liner from the line of fold to the foldable connection with the bottom, with the said fastening means and portion of the flange in each cut-out, is such to support the bottom of the liner section slightly above the bottom of the body section, and the length of the liner side walls is slightly shorter than the length of the respective body section wall panels.
